UNITED STATES PATENT OFFICE.

MORRIS MATHEWS, OF ST. JOSEPH, MISSOURI.

RUG-CLEANING MACHINE.

1,370,335.

Specification of Letters Patent.

Patented Mar. 1, 1921.

Application filed August 24, 1920. Serial No. 405,595.

To all whom it may concern:

Be it known that I, MORRIS MATHEWS, a citizen of the United States, residing at St. Joseph, in the county of Buchanan and 5 State of Missouri, have invented new and useful Improvements in Rug-Cleaning Machines, of which the following is a specification.

My present invention has reference to a 10 means whereby floor rugs may be cleaned in an easy and efficient manner.

The object of the invention is the production in a machine for this purpose, of a yieldably supported slatted bed on which 15 the rug rests, and the arrangement thereover of brush members that are movable longitudinally from the rug for cleaning the same.

A further object is the provision, in a rug 20 cleaning machine, of a frame including a receptacle in which may be arranged a cleaning fluid, and which has also arranged therein a resiliently supported slatted bed on which the rug to be cleaned rests, means being provided for clamping the rug on the bed, while arranged for longitudinal movement over the rug are endless belts carrying brush members which engage with the rug for cleaning the same, means being provided 25 for regulating the pressure of the brushes against the rugs, and means being provided for elevating the brushes above the rug when the latter is to be positioned in or removed from the machine.

30 The foregoing, and other objects which will appear as the nature of the invention is better understood, may be accomplished by a construction, combination and operative arrangement of parts, such as is disclosed by the drawings. The nature of the 35 invention is such as to render the same susceptible to various changes in size, proportion, and other modifications, so the drawings are to be understood as merely illustrative, and that I am entitled to all such changes therefrom as fall within the scope 40 of the appended claims.

In the drawings:—

Figure 1 is a side elevation of a rug cleaning machine constructed in accordance with 50 this invention.

Fig. 2 is a similar view looking toward the opposite side.

Fig. 3 is a top plan view.

55 Fig. 4 is a sectional view approximately on the line 4—4 of Fig. 3.

Fig. 5 is a detail view illustrating the manner in which the brush supporting frame is retained elevated when a rug is to be arranged in the machine for cleaning. 60

Fig. 6 is an end elevation.

Fig. 7 is a sectional view on the line 7—7 of Fig. 4.

Fig. 8 is a fragmentary view, parts being in section, and illustrating more clearly the 65 manner in which the rug to be cleaned has one of its ends clamped on the base.

As disclosed by the drawings, my improvement includes a substantially rectangular base 1. The base may be constructed of any 70 desired material and may receive therein a cleaning fluid, as will hereinafter be more fully apparent. The base, at what I will term the rear end thereof is supported on short legs 2, and on the front end by legs 3 75 that project a suitable distance above the base and that have their upper ends connected by a cross piece 4.

Arising from the sides of the base, adjacent to the rear thereof are spaced pairs of 80 guide plates 5 which are connected at their upper ends by a cross piece 6. Between the pairs of guide plates are the side members 7 of a substantially U-shaped frame 8. The sides 7 may be tongued at the edges thereof 85 and the confronting faces of the pairs of guide plates may be grooved to receive the said tongues. The upper or connecting member for the frame is indicated by the numeral 9. Between the cross member 9 of 90 the U-shaped frame and the cross piece 6 of the guide plate 5 there are adjusting means, broadly indicated by the numeral 10. These means are preferably in the nature of threaded members which are secured to the member 9 and that pass through openings in the cross piece 6, the said threaded members being engaged by nuts 11 which contact with the outer face of the cross piece and thus hold the frame vertically adjusted with respect to the base of the device. 100

Passing through bearing openings in the side members 7 of the frame is a shaft 12. On one of the ends of this shaft is a belt wheel 13 designed to have a belt therearound 105 which is hitched to a suitable source of power (not shown). The opposite end of the shaft has keyed or otherwise secured thereon a toothed wheel 14. Journaled in suitable bearing openings in the side members 7 of the frame 8, below the shaft 12 is a second shaft 15. This shaft has on its 110

outer end a pinion 16 which is in mesh with the toothed wheel 14.

On the shaft 15, inward of the side members of the frame are sprocket wheels 17. 5 If desired these wheels may be toothed.

In the substantially rectangular base there is a bed comprising longitudinal members 18 connected by cross slats 19. The slats have their upper faces rounded, and are preferably semi-circular in cross section. The 10 longitudinal members, at the rear ends of the base are connected by a flat plate 20 which has secured on the upper face thereof clips 21 that are designed to engage with the rug when the same is arranged on the bed to be cleaned. The frame constituting the bed is influenced in an upward direction in the base by springs 22, which are preferably arranged at the corners of the bed in 15 contact with the longitudinal members 18 thereof. Thus it will be noted that the bed is yieldably supported.

To the sides of the base 1, directly inward of the guide plates 5 there is pivoted, as at 25 23, the side members 24 of the brush supporting frame. The side members 24 have journaled therebetween, at approximately the center and adjacent to the upper edges thereof, a roller 25. At the end of the brush 30 supporting frame, opposite that provided with the pivots 23, there is journaled a transverse shaft on which there are keyed sprocket wheels 26. Around these wheels and around the sprocket wheels 17 are trained endless 35 sprocket chains 27. Arranged transversely of the brush frame, and secured to the opposed chains 27 of the head members 28 are brushes 29. It will be apparent that when the main or drive shaft 12 is revolved, 40 the toothed wheel 14 thereon meshing with the pinion 16 will revolve the shaft 15, causing the chains 27 to travel longitudinally of the device, and thus revolve the brushes over the bed. The front ends of the side members 45 of the brush frame are connected by a yoke 30 that has a central finger portion 31 that passes through the opening 32 in the cross piece 4. If desired, a spring may be arranged between the finger and the yoke to 50 force the front end of the brush frame toward the bed, such spring being indicated by the numeral 33. On the cross piece 4, above the finger is a bracket 34 having a sheave wheel 35 pivoted thereon, and secured 55 to the finger and trained around the sheave wheel is a cord or cable 36 that is directed toward the cross piece 6 for the guide plates 5. On the cross piece 6 there is a drum 37 that has its shaft 38 journaled in a suitable 60 frame or support 39, and around this drum the end of the cable 36 is wound. The shaft for the drum has an offset portion providing a crank handle 40 whereby the drum may be turned, and the cable wound to elevate 65 the forward end of the frame. If desired,

suitable pawl means may be provided between the drum shaft and the support therefor, while on the ends of the brush frame I pivotally secure supports 41, which, when swung angularly against the bed will hold 70 the front end of the brush frame elevated so that a rug to be cleaned may be arranged on the bed and engaged by the spring clips 21.

If desired, a cleaning fluid may be received in the tank-like body 1, and as the 75 brushes are continuously passed over the rug which is arranged on the bed, the said rug can be cleaned in an easy, quick and thoroughly efficient manner.

Having thus described the invention, what 80 I claim, is:

1. In a rug cleaning machine, a yieldably supported slatted bed on which a rug to be cleaned is placed, means for clamping a rug thereon, a pivotally supported frame 85 thereabove, brushes mounted on endless carriers on the frame, means for swinging the frame to bring the brushes in contacting engagement with the rug, and means for imparting motion to the carriers for moving 90 the brushes over the rug.

2. In a rug cleaning machine, a yieldably supported slatted bed on which a rug to be cleaned is placed, means for clamping a rug 95 thereon, a pivotally supported frame thereabove, brushes mounted on endless carriers on the frame, means for swinging the frame to bring the brushes in contacting engagement with the rug, and means for imparting motion to the carriers for moving the brushes 100 over the rug, and means for controlling the frictional engagement of the brushes with the rug.

3. In a rug cleaning machine, a hollow base having legs supporting the same, a 105 spring supported slatted bed in the base designed to receive a rug to be cleaned thereon, means for clamping a rug to the base, a vertically adjustable substantially U-shaped frame mounted in guides on the base, shafts carried thereby, a frame in the base pivoted adjacent to the adjustable frame and including transverse rollers, endless belts trained around said rollers, and the lower shaft of the adjustable frame, brush heads carrying brushes secured to the endless belts, means for revolving the shafts of the adjustable frame, means between the shafts whereby simultaneous motion is imparted to both of the shafts, and means at the front 115 end of the brush frame for adjusting the same whereby to permit of the arrangement of the rug on the bed and to bring the brushes into proper contacting engagement with the rug.

4. In a rug cleaning machine, a hollow base designed to receive a cleaning fluid therein, a spring supported slatted bed in the base designed to receive a rug to be cleaned thereon, means for clamping the rug 120

on the base, guides arising from one end of the base, a substantially U-shaped frame in the guides, means for vertically adjusting the frame, shafts carried thereby, interengaging means between the shafts whereby both of the shafts are turned in unison, means for imparting motion to one of the shafts, a frame in the base, pivoted adjacent to the guides, rollers between the side members of the frame, pulley wheels on the outer rollers, pulley wheels on the lower shaft of the adjustable frame, endless belts

trained around the pulleys, brush heads carrying brushes secured to the belts, pivoted supports on the brush frame, a spring influenced yoke on the outer end of the brush frame whereby to move the same to bring the brushes in rug engaging position, and cable operating means connected with the yoke for regulating the frictional engagement of the brushes with the rug. 15 20

In testimony whereof I affix my signature.

MORRIS MATHEWS.
